UNITED STATES PATENT OFFICE.

JACOB H. KAPLAN, OF CHICAGO, ILLINOIS.

DESIGN FOR A PROSTHETIC LAMP.

Application filed February 10, 1928. Serial No. 25,356. Term of patent 7 years.

To all whom it may concern:

Be it known that I, JACOB H. KAPLAN, a citizen of the United States, residing at Chicago, in the county of Cook and State of Illinois, have invented a new, original, and ornamental Design for a Prosthetic Lamp, of which the following is a specification, reference being had to the accompanying drawing, forming a part thereof.

Figure 1 is a side elevation of a prosthetic lamp, showing my new design.

Figure 2 is a top plan view of Figure 1.

I claim:

The ornamental design for a prosthetic lamp, as shown.

JACOB H. KAPLAN.
